UNITED STATES PATENT OFFICE.

ANDREW MARCINKO, OF JOLIET, ILLINOIS.

ARTIFICIAL LIMB.

1,299,980.

Specification of Letters Patent.

Patented Apr. 8, 1919.

Application filed January 7, 1919. Serial No. 270,072.

To all whom it may concern:

Be it known that I, ANDREW MARCINKO, a citizen of U. S. A., residing at Joliet, in the county of Will and State of Illinois, 5 have invented new and useful Improvements in Artificial Limbs, of which the following is a specification.

This invention has reference to an improvement in artificial limbs.

10 The primary object of the invention is to provide an artificial limb to take the place of a leg removed at the hip of a person, which comprises means whereby the same will be readily attached and conveniently 15 supported by the person and will permit of movement thereof substantially similar to the movement of a person's leg from his hip, by motion from the body of the person.

Other objects and advantages will present 20 themselves as the nature of the invention is better understood, reference being had to the accompanying drawings, in which:

Figure 1 is a front elevation illustrating 25 the application of the improvement.

Fig. 2 is a side elevation thereof.

Fig. 3 is a rear elevation.

Fig. 4 is a sectional view through the improvement, approximately on the line 30 4-4 of Fig. 1.

Fig. 5 is a substantially similar sectional view but showing the arrangement of parts as when the body of the wearer is bent to break the joint between the artificial leg 35 and the support therefor.

Fig. 6 is a sectional view through the improvement, approximately on the line 6-6 of Fig. 2.

Fig. 7 is a perspective view of the improvement looking toward the inner side thereof.

The supporting element or socket of the improvement is constructed of some pliable material, preferably including an outer portion 45 constructed wholly of leather and an inner cushioning member. The socket 10 has its inner face open, and its inner edge at the upper corner thereof extended to provide a strap 11, its opposite upper corner 50 also extended and provided with a buckle 12 to receive the strap, whereby the device may be secured upon the person of the wearer and the stub at the portion of the body from which a limb has been removed 55 is received in the socket. It is, of course, to be understood that the socket is shaped

to snugly receive the hip portion of the wearer and that the inner edge thereof is disposed to one side of the crotch. Thus the socket is not contacted by the remaining 60 leg of the wearer or by any of the parts of the wearer except the hip and stub of the leg, the abdomen to one side of the center of the body, the back, and, of course, the waist around which the strap 11 is arranged. 65 Both the abdomen and the back of the wearer are braced by a metallic band which is rounded around the outer portion of the socket 10 adjacent to the upper edge thereof, the said rounded band being indicated by 70 the numeral 13. The metallic band is secured to the flexible socket in any desired or preferred manner and has its ends terminating in a line with the outer edge of the socket at the open side thereof. To the 75 ends of the band 11 is secured a metallic casting in the nature of a strap 14 which conforms to the shape of the socket and is, of course, arranged at the open side thereof. The curved or rounded strap 14 may be integrally formed with the band 13 and is secured to the socket 10. The lower and central portion of the strap 14 is thickened as at 15 and the said thickened portion is provided with a transverse extension 16 80 arranged directly below and corresponding to the shape of the bottom portion of the socket 10. This extension 16 is extended around the outer side of the socket as indicated by the numeral 17 and is secured approximately centrally to the band 13. The extension, at the juncture of the portion 17 therewith is provided with a widened or thickened portion 18. Connected to the extension 17, the band 13 and to the socket 85 10, at the front thereof is a metallic strap 19 that conforms to the shape of the socket. Of course, this strap 14 may be integrally formed with the remaining metallic elements above recited. The widened or thickened portions 17 and 18 provide the metallic reinforcements for the socket with lugs, and these lugs have their outer faces straight and are provided with apertures 90 through which pass pivot members 20 that connect plates 21 to the metallic reinforcement, and these plates are let in the opposite sides of the artificial limb 22. The limb 22 has its upper portion hollow and open for a suitable distance from the upper end 95 thereof on its back or rear portion, and the sides, at the top of the divided portion of 100 105 110

the leg are braced by a metallic strap or band 23 that is secured to the artificial limb.

On the strap 19, adjacent to the connection thereof with the extension 16 is an outwardly projecting bifurcated lug 24. In the bifurcated lug is pivoted, as at 25, a rod 26 that is adjustably received in and secured to the hollow outer portion of a link 27. The link 27 is hingedly connected, as at 28 to a second and flat link 29, the last mentioned link being hingedly secured, as at 30 in the hollow portion of the artificial limb 22, at the front of the said limb. The link 30 is provided with an elongated slot 31 which receives therein the notched shank 32 of a latch member 33. The latch has its outer end provided with a head 34 that is arranged exteriorly of the slotted face plate of the keeper 35 for the latch. In the keeper 35 is a spring 36 which bears against the latch, normally influencing the same in one direction. The head or outer end of the latch has its lower edge arranged at an angle as indicated by the numeral 37.

When the device is strapped upon the person of the wearer, in a manner as heretofore described a pressure of the wearer's body in a forward direction, with the outer end of the limb resting upon the ground, will break the joint between the links, causing the latch to disengage the link 30. When the wearer brings his body back to normal vertical position the links will be swung to alining position and the catch will engage with the link 30, thus locking the leg vertically with respect to the body of the wearer.

It is believed, from the foregoing description, when taken in connection with the drawings, the simplicity and advantages of the construction will be readily apparent without further detailed description.

Having thus described the invention, what is claimed as new, is:—

1. In a device of the class described, a flexible socket, attaching means therefor, curved metallic brace members secured to said socket, an artificial limb pivotally connected to said brace, jointed members piv-

oted to the brace and to the limb, and means for engaging one of the members to hold both of said members in normal longitudinal alinement.

2. In a device of the class described, a flexible socket, attaching means therefor, curved metallic brace members secured to said socket, an artificial limb pivotally connected to said brace, jointed members pivotally connected to the brace and limb respectively, and spring influenced means for engaging one of the members to hold both of said members in normal longitudinal alinement.

3. In a device for the purpose set forth, a flexible socket having an open side, attaching means for said socket, curved metallic brace members secured to the outer face of said socket, one of which being arranged at the outer edge of said socket, an artificial limb pivotally connected to other of said braces, jointed links one of which being hingedly secured in the limb and the other adjustably connected to one of the braces, and spring influenced means on the limb for engaging with one of the links for holding both of said links in normal longitudinal alinement.

4. In a device of the class described, a flexible socket having an open side, an attaching strap adjustable on said socket, curved metallic brace members secured to the outer surface of said socket, one of which being arranged at the upper edge thereof, another at the open end thereof, another at the side thereof and the last at the front thereof, an artificial limb pivotally secured to the brace members at the lower portions thereof, jointed links one of which being hingedly connected in the limb, the other being adjustably pivoted to the center brace member, one of said links having a slot therethrough, and a spring influenced catch carried by the limb received in said slot to hold the links in normal longitudinal alinement.

In testimony whereof I affix my signature.

ANDREW MARCINKO.

Copies of this patent may be obtained for five cents each, by addressing the "Commissioner of Patents, Washington, D. C."
